APPARATUS FOR MAKING OF PHOTOGRAPHIC CONTACT COPIES OF DOCUMENTS

Filed July 24, 1940

UNITED STATES PATENT OFFICE

2,252,562

APPARATUS FOR MAKING OF PHOTOGRAPHIC CONTACT COPIES OF DOCUMENTS

William Ganley, New York, N. Y.

Application July 24, 1940, Serial No. 347,183

4 Claims. (Cl. 95—73)

My invention relates to that class of devices designed to provide quick and simple means to produce copies of printed or written documents. In devices of that character with which I am familiar it is found difficult to obtain clear prints of the matter at the extreme edges of the page which is being reproduced. Also in making the prints, sheets of sensitized paper must be used. This limits to a considerable extent the usefulness of the device.

My invention has for its principal object to provide means which will greatly improve the effectiveness of the device by increasing the clearness of the print and producing a print which will be as clear and distinct at its edges as in the center.

A further object is to do away with the necessity of employing a fluorescent screen.

A further object is to provide a self-contained device having a continuous roll of sensitized paper therein, so that the number of copies which can be made is only limited by the length of paper in the roll.

My means of accomplishing the foregoing objects may be more readily understood by having reference to the accompanying drawing which is hereunto annexed and made a part of this specification in which:

Fig. 1 is a vertical sectional view of a device embodying my improvement.

Fig. 2 is a section on the line 2—2 in Fig. 1.

Fig. 3 is a top or plan view with the glass plate removed in Fig. 1.

Fig. 4 is an enlarged detail view of the roll of sensitized paper showing its mounting.

Fig. 5 is a detail view in section of my improved plate.

Fig. 6 is a cross-section of a lamp equipped with means to obviate the necessity of using a fluorescent plate.

Similar reference numerals refer to similar parts throughout the entire specification.

As shown in the drawing, I provide a container or box having top, bottom, end, and side walls 1, 2, 3, 4 and 5 respectively. The top wall 1, is preferably secured to the end wall 3, by means of a hinge 6. Below the top wall 1, I mount a plate of transparent glass 7, the lower surface of which is given a coating of green zinc sulfide 8 ($ZnS \cdot H_2O$) produced by adding copper sulfate ($CuSO_4 \cdot 5H_2O$) to the zinc sulfide. The upper surface is coated with a canary yellow zinc sulfide 9, which is produced by adding cadmium sulfide (CdS) and chloride (C, Cl). Below this plate 7,

are mounted one or more electric light bulbs or tubes 10. In practice I have found those known to the trade as "Lumaline" tubes, although the ordinary incandescent light bulb properly distributed within the container will give the same results. Therefore, the terms "bulbs" or "tubes" where used in my description are synonymous. These tubes are connected by means of electric wires 11 and 12, to a source of electric current (not shown). An automatic switch 13, may be utilized if desired, the switch 13 may be set for the correct amount of time required for the exposure.

At one end of the container I construct a light tight chamber 14, in which is mounted a roll 15, of sensitized paper. Bearings 16 and 17, for the roll 15, are secured to the side walls 4 and 5, in any suitable or convenient manner. A slot 18, is cut in the wall 19, of the chamber 14, through which the sensitized paper may be drawn over the glass plate 7. The upper edge 20, of the slot 18, is preferably provided with a knife edge by means of which the operator may tear or cut off the desired length of paper for the print to be made.

The top wall 21, of the chamber should be either hinged as shown or made easily removable, so as to permit easy access to the chamber for the purpose of loading the roll 15, in place.

I have found in practice that a highly satisfactory print can be made by using the glass plate, formed of diffusing glass instead of transparent and then coating the electric light bulbs or tubes 10, as seen in the detail view Fig. 6, with green or yellow zinc sulfide, and arranging the tubes alternately one green, one yellow across the entire container as shown in Figure 3. When this is done a very even print is produced.

Operation

The operation of the device is as follows: The top wall 21, of the chamber 14, is opened and a roll of sensitized paper 15, is inserted in the bearings 16 and 17. The top or lid wall 21 is then closed, and the correct amount of paper is drawn through the slot 18, and laid upon the glass plate 7, with the emulsion side uppermost. The document which is to be reproduced is then placed on the paper. A suitable platen 22, which has spring arms by means of which it may be held tightly against the document and paper is then placed on top of them, the switch is thrown connecting the electric light tubes 10, to the source of electric current (not shown). The light emitted by the tubes 10, will be ab-

sorbed by the activation of the fluorescent material on either the tubes 10, or the glass plate 7.

After the exposure has been made for a few seconds the electric current is automatically turned off. The sensitized paper 15, is dipped into a solution of MQ forming a negative. It can then be put into a fixing solution and the negative will be made light-proof. Afterwards as many positive copies may be made as required.

Although I have described with more or less particularity specific details of construction, I do not wish to be understood as intending to be limited thereby, since they are merely to illustrate a concrete embodiment of my invention, as changes in the details may be made in commercial production. Therefore I do not desire to be limited to the exact disclosure except where such limitations appear in the hereinafter appended claims.

Having described my invention what I regard as new and desire to secure by Letters Patent is:

1. In a device of the character described to reproduce printed or other material on sensitized paper; a container having top, bottom, end, and side walls, a diffusing plate of glass therein, a coating on one side of said plate of green zinc sulfide, a coating on the other side of yellow zinc sulfide, an electric light source in said container below said plate, and means to connect current to said light source.

2. In a device of the character described to reproduce printed or other material on sensitized paper a container having top, bottom, end, and side walls, a light-proof chamber at one end of said container, means to detachably

mount a roll of sensitized paper in said chamber, there being a slot in the wall adjacent the top of the container through which the sensitized paper may be drawn, the upper edge of 5 said slot having a knife edge whereby the paper may be cut off in desired lengths, a plate of transparent glass therein, a coating on one side of said plate of green-zinc sulfide, a coating on the other side of yellow zinc sulfide, an electric 10 light source in said container below said plate, and means to convey current to said light source.

3. In a device of the character described to reproduce printed or other material on sensitized paper; a container having top, bottom, end, and side walls, a transparent plate of glass therein, a coating on one side of said plate of green zinc sulfide, a coating on the other side of yellow zinc sulfide, an electric light source in 15 said container below said plate, means to connect current to said light source, and means to hold the material to be reproduced tightly against said sensitized paper on said glass plate.

4. In a device of the character described to reproduce printed or other material on sensitized paper; a container having top, bottom, end, and side walls, a plate of material which will transmit light rays having one side treated with a phosphorescent emulsion of green color for storing light for a period of time and then emitting it, the other side of said plate being coated with a similar emulsion of yellow color, an electric light source in said container below 20 said plate, and means to connect current to said light source.

WILLIAM GANLEY.
